UNITED STATES PATENT OFFICE

112,172

DESIGN FOR A REVOLVING CONTAINER FOR DRINKING GLASSES

Louis J. Gordon, Chicago, Ill.

Application July 15, 1938, Serial No. 78,515

Term of patent 7 years

To all whom it may concern:

Be it known that I, Louis J. Gordon, a citizen of the United States, residing at Chicago, in the county of Cook and State of Illinois, have invented a new, original, and ornamental Design for a Revolving Container for Drinking Glasses, of which the following is a specification, reference being had to the accompanying drawing, forming part thereof.

Fig. 1 is a top plan view of the revolving container for drinking glasses showing my design.

Fig. 2 is a side elevational view of the same.

I claim:

The ornamental design for a revolving container for drinking glasses, as shown.

LOUIS J. GORDON,
